UNITED STATES PATENT OFFICE

23,477

PNEUMATIC COTTON HARVESTER

Raymond Henry, Moline, Ill.

Original No. 2,531,042, dated November 21, 1950,
 Serial No. 114,577, September 8, 1949. Appli-
 cation for reissue May 26, 1951, Serial No.
 228,481

13 Claims. (Cl. 56—12)

Matter enclosed in heavy brackets **1** appears in the original patent but forms no part of this reissue specification; matter printed in italics indicates the additions made by reissue.

1

My present invention relates to means for increasing the rate of flow of air through the cotton bushes and into the collector. The purpose is not to produce a vacuum but to produce a high rate of movement of air through the bushes, whereby to pull the cotton out of the bolls and force it into a collector, shown as a wire mesh cage. An incidental object is to increase the rate at which cotton can be gathered. An additional object is to decrease the cost of harvesting the cotton crop. I have, also, such further objects, advantages, and capabilities as will hereafter appear and as are inherent in the structure disclosed herein. My invention further resides in the combination, construction, and arrangement of parts illustrated in the accompanying drawings and, while I have shown therein what is now regarded as the preferred embodiment of this invention, and a modification thereof, I desire the same to be regarded as illustrative only and not to be interpreted in a limiting sense.

In the drawings annexed hereto and forming a part hereof,

Fig. 1 is a side elevation of a machine embodying my present invention;

Fig. 2 is a plan view of such a machine in a cotton field, with parts removed;

Fig. 3 is a front elevation of the structure shown in Figs. 1 and 2;

Fig. 4 represents a fragmentary radial section of one of the wind-producing units, the section being taken substantially along the plane indicated by the line **4—4**, of Fig. 1;

Fig. 5 is a plan view of a structure for picking cotton from two rows, simultaneously, embracing the two rows between the picking elements; and

Fig. 6 represents a machine for picking the cotton from a single row at a time, picking first from one side of the row and then from the other side.

Reference will now be made in greater detail to the annexed drawings for a more complete description of this invention. In Figs. 1, 2, and 3, there is shown a somewhat skeletonized framework **10**, connected at its rear end to an axle **11** upon which is mounted a motor **13**, preferably an internal combustion motor, although I do not wish to exclude the use of other motive means for propelling the machine. For example, a storage or secondary battery may be mounted on the framework **10** and used to drive an electric motor whereby to drive the picker through the field.

At the outer ends of the axle **11** are mounted supporting wheels **12** which support the framework **10** and the axle **11** for transport through a

2

field. The motor shown in Figs. 1 and 2 is represented as an internal combustion motor **13** which is shown as connected in driving relation to a ground-engaging wheel **14** which may be lifted out of ground-engaging position by means of a handle **15**. The driving connection between the motor **13** and the ground-engaging wheel **14** is illustrated as a V-belt **14a**, by reference.

At the front of the machine is shown a ground-engaging wheel **16** for supporting the front end of the framework **10** and the operative mechanism supported thereby. A platform **17**, shown plainly in Fig. 2 but omitted in the other figures, is connected at its two ends to the framework **10** and serves to support the casings **18** and the motors **19**, each provided with a motor shaft **19a** by which the rotors **20** are rotated. These rotors are each mounted on an end of the shaft of a motor **19** and, by preference, are about forty inches (40") in diameter, which results in the speed at which the peripheral surface of the rotor travels being approximately one hundred and thirty (130) miles per hour. Each rotor **20** has a motor of its own so that blocking of an entrance for the air will not force a greater amount of air through another entrance and permit the easy closure of the partially blocked entrance.

In Fig. 1, the rotor **20** is seen through an opening **21** in the housing **18**. This opening **21**, in actual practice, is approximately five-sixteenths of an inch ($\frac{5}{16}$ ") in width which permits the cotton seeds to enter with the cotton, although it may be found, by further practice in the field, that some other size of opening may be preferable. The housing **18** has a peripheral channel **22** into which the cotton is forced by the rotor **20**. The rotor is a cast plate, preferably of aluminum, with a large number of blades **23** which cause the air to enter through the opening **21**, between the crossbars **24** which hold the plate **25** centered with relation to the face of the housing **18**.

As stated above, the opening between the edge of the plate **25** and the surrounding flange **26** is approximately five-sixteenths of an inch ($\frac{5}{16}$ ") in width to permit passage of the cotton and its seeds. Likewise, the opening between the face of the rotor **20** and the flange **26** is approximately the same. The edges of the plate **25** and the flange **26** are rolled over, as shown at **29** and **31** in Fig. 4, to reduce friction to as small an amount as possible for the entering cotton.

The blades **23** force the air in the housing **18** out through the channel **27**, thus causing the air to go into the basket **28**. The edges of the blades **23** are rounded, as shown at **29** in Fig. 4, to assist

in preventing the air from going out of the casing through the entrance slot.

From what has been said, it will be clear that the rotor 20 of the respective fans or blowers is concentric with its associated casing 18, as shown in Figure 1, and, with the blades 23, constitutes a high speed radial discharge fan or blower. The motor shaft 19a extends transversely of the harvester frame in a substantially horizontal plane and at an inclination thereto, as shown. The rotor 20 being mounted on and driven by shaft 19a rotates about the axis thereof and is inclined lengthwise of the frame in a substantially vertical plane. Likewise, the casing 18 is inclined lengthwise of the harvester frame with the opening 21 directed toward one side of the frame. The radially outer portion of casing 18 defines the channel 22 which opens radially inward of casing 18 and extends radially outward thereof beyond the fan, as shown in Figure 4. During travel of the harvester along a row of cotton plants, the side of casing 18 having the annular opening 21 wipes along the plants of the row, as shown in Figures 2, 5 and 6 of the drawings, and the cotton is blown into casing 18 through the opening 21, by the entering high velocity air stream, and is expelled from channel 22 of casing 18 through the discharge channel or passage 27, by the action of the fan or blower, as previously explained.

The form of structure shown in Figs. 1 to 4 is adapted, as is evident from Fig. 2, to straddle two rows and pick from them simultaneously on the inside faces of the rows, while the structure of Fig. 5 straddles two rows and picks from them simultaneously on the outside of the rows. This structure can be guided in the field by turning the wheel 14 by means of the handle 32.

The structure of Fig. 6 is designed to pick on both sides of a single row, first on one side and then on the other. This structure is supported on two pairs of wheels 12 and 33, and these wheels are dirigible, after the manner of automobile wheels. This vehicle is towed by means of the tongue 34 which serves as a steering means, as in the case of a wagon or other trailing vehicle.

It is of course understood that the specific description of structure set forth above may be departed from without departing from the spirit of my invention as disclosed herein and as defined in the appended claims.

Having now described my invention, I claim:

1. A machine for picking cotton comprising, in combination, transporting means, a frame supported thereby, a platform on said frame, a plurality of power units mounted on said platform, a plurality of casings supported by said platform, a shaft extending from each of said power units into a casing, there being but one power unit to a casing, and a high speed rotary fan mounted coaxially on each shaft, said fans having outwardly extending blades around their outer parts, said casings having ring-shaped openings through one flat wall thereof concentrically placed with relation to the fans, so that, as the fans rotate, air is drawn into the casings to replace the air forced out by the blades of the fans, said casings having peripheral channels around the fans for reception of the air and cotton driven outwardly by the fans, the air being forced outwardly by the fans at such a velocity that the air entering the ring-shaped openings will carry along with it the cotton on the plants in a field.

2. A structure as defined by claim 1 having the casings spaced laterally from each other and in-

clined in a horizontal plane whereby to engage rows of cotton on opposite sides of the rows.

3. A structure as defined by claim 1 in which the casings have the central part omitted and a circular plate mounted in each space from which the central part is omitted, said circular plates being mounted concentrically in said openings whereby to produce ring-shaped openings between the edges of the plates and the surrounding casing walls.

4. In a pneumatic cotton harvester having a plurality of supporting wheels and a supporting framework carried thereby; the improvements thereon consisting of a plurality of motors supported by said framework, and a flat casing in operative relationship to each motor, the casings being positioned at a small angle with relation to each other and spaced slightly laterally with regard to a central plane of the machine, whereby to engage opposite sides of bushes from which cotton is to be picked, said motors having shafts on which are mounted discs provided at their peripheries with blades parallel to their axes, the casings having peripheral channels surrounding the discs and their blades, said peripheral channels having discharge openings extending tangentially outwardly from the casings, and each casing having a lateral opening in one wall concentric with a motor shaft.

5. A structure as defined by claim 4 provided with a cotton catcher into which the cotton is blown by the discs.

6. A structure as defined by claim 4 provided with a drive wheel for propelling the picker in a field, and a motor for driving the propelling wheel.

7. A structure as defined by claim 4 in which the disc is driven at a speed to cause entrance of air into and exit thereof from the casing at a speed of at least one hundred and twenty (120) miles per hour.

8. In a pneumatic cotton harvester, a conveying vehicle, a motor supported thereby and provided with a substantially horizontal shaft, a casing carried by said vehicle, a high speed fan mounted on said shaft and rotating in a substantially vertical direction, said casing having a peripheral channel concentric with the fan, said picker having a cotton-receiving container for reception of cotton from the casing, a connection between the casing and the container for carrying the cotton from the one to the other, and means providing a narrow annular opening through one side of the casing opposite the lateral peripheral part of the fan through which air enters to replace air driven out through said connection, said air entering the casing by passing through the cotton on the bushes at a high enough rate of flow to remove the cotton from the bushes.

9. In a machine for picking cotton, transporting means, a frame supported thereby, a power unit mounted on said frame, a fan casing on said frame, and a radial discharge fan in said casing driven by said power unit, said casing having a peripheral channel around said fan and being provided with an annular inlet opening substantially concentric with said fan remote from the center and adjacent the periphery thereof whereby air enters said casing at the periphery of said fan and is propelled by the latter radially outward into and along said channel, said casing having a discharge passage leading from said channel.

10. In a machine for picking cotton, transport-

ing means, a frame supported thereby, a power unit mounted on said frame, a fan casing on said frame, and a radial discharge fan in said casing driven by said power unit and having outwardly extending blades at its peripheral portion and remote from its center, said casing having a peripheral channel around said fan and being provided with an annular inlet opening substantially concentric with said fan and aligned with the blades thereof whereby air enters said casing at the periphery of said fan and is propelled by the latter radially outward into and along said channel, said casing having a discharge passage leading from said channel.

11. In a machine for picking cotton, transporting means, a frame supported thereby, a power unit mounted on said frame, a fan casing on said frame with its axis extending substantially transversely thereof, said casing being disposed with one axial side thereof directed toward one side of said frame for travel along a row of cotton plants in proximity thereto and a radial discharge fan in said casing driven by said power unit, said casing having a peripheral channel around said fan and being provided in said one side with an annular inlet opening substantially concentric with said fan remote from the center and adjacent the periphery thereof whereby air enters said casing at the periphery of said fan and is propelled by the latter radially outward into and along said channel, said casing having a discharge passage leading from said channel.

12. In a machine for picking cotton, transporting means, a frame supported thereby, a power unit mounted on said frame, a fan casing on said frame with its axis inclined transversely thereof in a substantially horizontal plane, said casing being inclined lengthwise of said frame in a substantially vertical plane, and a radial discharge fan in said casing driven by said power unit, said casing having a peripheral channel around said fan and being provided with an annular inlet

6
opening substantially concentric with said fan remote from the center and adjacent the periphery thereof whereby air enters said casing at the periphery of said fan and is propelled by the latter radially outward into and along said channel, said casing having a discharge passage leading from said channel.

13. In a machine for picking cotton, transporting means, a frame supported thereby, a power unit mounted on said frame, a fan casing on said frame, and a radial discharge fan in said casing substantially coaxial therewith and driven by said power unit, the common axis of said casing and fan being inclined transversely of said frame in a substantially horizontal plane and said casing and said fan being inclined lengthwise of said frame in a substantially vertical plane, said casing being provided in one axial side thereof with an annular inlet opening concentric with said fan remote from the center and adjacent the periphery thereof whereby air enters said casing at the periphery of said fan and is propelled by the latter radially outward into and along said channel, said casing having a discharge passage leading from said channel.

RAYMOND HENRY.
